DES. 2232

Oliver T. Sage, of Boston, Mass.

Letters Patent No. 2,232 - Dated Dec. 18, 1865

Design for an Advertising Carriage

The schedule referred to in these letters Patent is made part of this specification.

To all whom it may concern:

Be it known that Oliver T. Sage, of Boston, in the County of Suffolk, and State of Massachusetts, have invented a new design for an advertising carriage, of which the following is a full, clear and exact description, reference being had to the accompanying drawings, making part of this specification, in which

Fig. 1 is a view of one side of my advertising carriage.

Fig. 2 is a rear elevation of the same.

Fig. 3 is a front elevation of the same.

My invention consists in a vehicle, the body of which is formed to represent a travelling trunk, and being driven about the streets to serve as an advertising medium, for displaying the name and place of business of the proprietor, while the hollow bottom answers as an express wagon to deliver the goods thus advertised. To enable others skilled in the art to understand and use my invention, I will proceed to describe the manner in which I have carried it out.

In the said drawing A represents the ordinary running gear of a vehicle which is placed in a hollow body B, made in the form of a travelling trunk, to the top of which is secured a strip, C, bearing my advertisement, viz: "Sage's Trunk Depot 546 Washington Street."

On the rear end (fig. 2) the name and place of business is again displayed, viz: "Sage's Trunk Depot 546 Washington Street."

Claim

What I claim as my invention and desire to secure by Letters Patent is: The above described design for an advertising carriage, viz: the body B, in the form of a travelling trunk supported on ordinary carriage running gear A, substantially as set forth.
